UNITED STATES PATENT OFFICE.

FRANK W. STACEY, OF SEATTLE, WASHINGTON, ASSIGNOR TO J. W. POWER, OF
SEATTLE, WASHINGTON.

DESIGN FOR AN AUTOMOBILE-RADIATOR ORNAMENT.

51,615.

Specification for Design.

Patented Dec. 18, 1917.

Application filed July 2, 1917. Serial No. 178,263. Term of patent 3½ years.

To all whom it may concern:

Be it known that I, FRANK W. STACEY, citizen of the United States, residing at Seattle, in the county of King and State of Washington, have invented a certain new, original, and ornamental Design for an Automobile - Radiator Ornament, of which the following is a specification, reference being had to the accompanying drawing, forming a part thereof.

The figure of the drawing is a view showing my new design, which comprises a fac-

simile of a projectile of a gun having associated therewith a plurality of flags, said projectile being provided with means for attaching it to a suitable support, as an automobile radiator.

What I claim is:

The ornamental design for an automobile radiator ornament as shown and described.

In witness whereof I hereunto subscribe my name this 23rd day of June, A. D., 1917.

FRANK W. STACEY.
